REFRIGERATING APPARATUS

Charles F. Henney, Dayton, Ohio, assignor to
General Motors Corporation, Dayton, Ohio, a
corporation of Delaware

Application April 18, 1934, Serial No. 721,173

4 Claims. (CL 62—117)

This invention relates to refrigeration and more particularly to the conditioning of air for passenger cars.

It is an object of this invention to provide an improved mode of conditioning air for the passenger space of a car in a simplified and efficient manner.

Further objects and advantages of the present invention will be apparent from the following description, reference being had to the accompanying drawing, wherein a preferred form of the present invention is clearly shown.

In the drawing:

Fig. 1 is a diagrammatic representation of an apparatus embodying the features of my invention; and

Fig. 2 is a diagrammatic representation of a plane view of a car embodying features of my invention.

A car 10 having a space or compartment 11 to be conditioned is provided with a refrigerating system of a type diagrammatically shown in Fig. 1. The space to be conditioned generally includes rows of seats 12 along the longitudinal edges of the relatively long compartment 11. Intermediate the ends of the compartment one or more cooling means 13 are placed in such a manner that oppositely directed and transversely spaced streams of air are blown through the cooling means in the upper part of the space or compartment and thus insures the conditioning of the air throughout the space.

Referring now more particularly to Fig. 1, the cooling means 13 may include refrigerant evaporating means in the form of two refrigerant evaporators 14 and 15 connected in refrigerant flow relationship with a refrigerant liquefying unit 16. The liquefying unit 16 may include a compressor 17, condenser 18, receiver 19 connected through the suction line 20 and the liquid line 21 with the evaporator. The compressor 17 preferably is driven by a motor 22. Oppositely directed blowers 23 and 24 are placed on opposite sides of the cooling means 13 and are transversely disposed with respect to each other and are arranged to blow the air in opposite and substantially parallel directions.

Means are provided for automatically controlling the evaporation of refrigerant in the evaporators 14 and 15. Such means may be made responsive to air conditions in space 11, thus a thermostatic bulb 25 is placed in the space 11 and controls the switch 26 which starts and stops the motor 22 either directly or through

proper relays. In addition, the liquid refrigerant line 21 is provided with branches 21a and 21b having automatic expansion valves 27 and 28 which control the entrance of refrigerant into the evaporators 14 and 15 respectively. The branches 20a and 20b of the suction line are in thermal contact with thermostatic bulbs 29 and 30 which throttle the valves 27 and 28 respectively when the evaporators tend to "spill over." The valves 27 and 28 automatically feed liquid refrigerant when the pressure in the evaporators is reduced below a predetermined pressure range except when the valves are throttled by the bulbs 29 and 30.

A single bank of coils may be placed substantially in the middle of the car, or several banks may be placed at spaced intervals along the length of the car. In either case, two oppositely directed streams of air are maintained in the upper part of car above the heads of persons seated in the car from which the cooled air drops gently into the lower part of the car without causing objectionable drafts.

While the form of embodiment of the invention as herein disclosed, constitutes a preferred form, it is to be understood that other forms might be adopted, all coming within the scope of the claims which follow.

What is claimed is as follows:

1. A car having a space to be conditioned, a plurality of cooling means intermediate the ends of said space and located in the upper part of the space, oppositely directed blowers transversely disposed to blow air over said cooling means in opposite and transversely disposed directions in the upper part of the space, the arrangement of said blowers and cooling means being such that air circulated flows in its cooled condition in the upper part of said space, means responsive to refrigeration conditions for independently controlling the cooling effect of said cooling means, and separate means for jointly controlling the effect of said cooling means.

2. A car having a space to be conditioned, a plurality of evaporating means intermediate the ends of said space and located in the upper part of said space, a common support for said means, oppositely directed blowers transversely disposed to blow air in opposite and transversely disposed directions, the arrangement of said evaporating means and blowers being such that air circulated by said blowers flows over said evaporators into the upper part of said space, means responsive to refrigeration requirements for independently controlling the evaporation of refrigerant in said

evaporating means, and means for controlling the starting and stopping of the flow of refrigerant in said evaporating means.

3. A car having a relatively long and narrow space to be conditioned, a plurality of cooling means arranged side by side intermediate the ends of the space and located in the upper part of the space, oppositely directed blowers transversely disposed to blow air over said cooling means in opposite and transversely disposed directions in the upper part of the space, the arrangement of said blowers and cooling means being such that air circulated flows in its cooled condition in the upper part of the space, means responsive to refrigeration conditions for independently controlling the cooling effect of said cooling means, and separate means for jointly controlling the effect of said cooling means in ac-

cordance with temperature conditions in said space.

4. A car having a space to be conditioned, evaporating means intermediate the ends of said space and located in the upper part of the space, oppositely directed blowers transversely disposed to blow air in opposite and transversely disposed directions in the upper part of said space, the arrangement of said evaporating means and blowers being such that air circulated by said blowers flows in its cooled condition in the upper part of said space, means for controlling the evaporation of refrigerant in said evaporating means in accordance with air conditions in said space, and means for balancing the load between 10 and 15 said evaporating means.

CHARLES F. HENNEY.
